(57) CLAIM

The ornamental design for a seven day fragrance bottle, as shown and described.

DESCRIPTION

FIG. 1 is a front view of the seven day fragrance bottle, showing my new design;

FIG. 2 is a rear view thereof;

FIG. 3 is a right-side view thereof;

FIG. 4 is a left-side view thereof;

FIG. 5 is a top, plan view thereof;

FIG. 6 is a bottom, plan view thereof; and,

FIG. 7 is an exploded, front view thereof.

The broken lines shown illustrate environmental structure of the seven day fragrance bottle that form no part of the claimed design.

1 Claim, 7 Drawing Sheets(56)
